UNITED STATES PATENT OFFICE

123,751

DESIGN FOR AN OPTICIAN'S FITTING TABLE

Vern W. Doty, Buffalo, N. Y.

Application May 25, 1940, Serial No. 92,612

Term of patent 3½ years

To all whom it may concern:

Be it known that I, Vern W. Doty, a citizen of the United States, residing at Buffalo, in the county of Erie and State of New York, have invented a new, original, and ornamental Design for an Optician's Fitting Table, of which the following is a specification, reference being had to the accompanying drawing, forming a part thereof.

Figure 1 is a front elevational view of the fitting table embodying my new design. Figure 2 is a top plan view thereof. Figure 3 is a rear elevational view of the same. Figure 4 is an end elevational view of the table.

I claim:

The ornamental design for an optician's fitting table, substantially as shown.

VERN W. DOTY.
